CLAIM

The ornamental design for a spraying head for cleaning dental plaque, as shown and described.

DESCRIPTION

FIG. 1 is a front view of a spraying head for cleaning dental plaque showing my new design;

FIG. 2 is a rear view thereof;

FIG. 3 is a right side view thereof;

FIG. 4 is a left side view thereof;

FIG. 5 is a top plan view thereof;

FIG. 6 is a bottom plan view thereof; and,

FIG. 7 is a perspective view thereof.

The broken lines are for the purposes of illustrating portions of the spraying head for cleaning dental plaque and form no part of the claimed design.

1 Claim, 7 Drawing Sheets
